CLAIM

The ornamental design for a tool positioning pad with surface pattern as shown and described.

DESCRIPTION

FIG. 1 is a perspective view of a tool positioning pad with surface pattern showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a partial enlarged front view thereof within the area designated as “8” in FIG. 2.
The dash-dash broken lines shown in the drawings depict portions of the article that form no part of the claimed design. The dot-dash broken lines annotate the enlarged view and form no part of the claimed design.

1 Claim, 8 Drawing Sheets
